J. R. PADESKY

INSTRUMENT PANEL

Filed Feb. 17, 1926

UNITED STATES PATENT OFFICE.

JOHN R. PADESKY, OF LA CROSSE, WISCONSIN, ASSIGNOR, BY MESNE ASSIGNMENTS, TO NATIONAL GAUGE & EQUIPMENT COMPANY, OF WILMINGTON, DELAWARE, A CORPORATION OF DELAWARE.

INSTRUMENT PANEL.

Application filed February 17, 1926. Serial No. 88,831.

This invention relates to improvements in instrument panels, particularly those panels adapted to the mounting of the indicating instruments which are usually employed in 5 motor vehicles and which are arranged near the seat of the operator and designed to be read by the operator.

An object of the invention is to provide a panel, so constructed and arranged, in connection with an associated electric light, as to permit of an indirect illumination of the faces of the indicating instrument; a further object being to provide a construction which will permit of an inexpensive installation of 10 the instruments and light upon the panel as a unit in a manner to secure an indirect lighting of the faces of the instrument.

Fig. 1 is a front elevational view of the panel; Fig. 2 is a transverse view on lines 2—2 of Fig. 1; Fig. 3 is a rear view with part of the instruments in place; Fig. 4 is a transverse view on lines 4—4 of Fig. 1; Fig. 5 is an enlarged sectional view on line 5—5 of Fig. 1 and Fig. 6 is a sectional view on lines 6—6 15 of Fig. 1.

Like parts are indicated by like figures throughout the different views.

The panel 1 is capable of being quickly applied to the dash of an automobile, there 20 being openings 2 for that purpose. There are shown openings for three instruments, the central space being vacant and a preferable arrangement is to have an ammeter and oil pressure gauge at each side with a speedometer 25 placed between the same, but it is not intended to limit the invention to that particular arrangement of instruments. The body of the panel is shown with the usual rib 3 projecting from the front face of the panel and this front face is preferably shown with 30 three openings 4 for exposure of the dial plates of the instruments 6 which are supported adjacent said openings 4. These openings have flanges 7 projecting rearwardly 35 from the rear face of the panel, cut away as indicated at 8 in Fig. 1 and these cut away portions 8 are all in radial lines taken from the electric light 9 as a center (Fig. 1). It is seen from an examination of the figures that 40 the opening 4 near the center of the panel has a circular flange with a cut away portion nearest the point where the electric light is supported and in a direct line with the same, 45

while the openings 4 for the other instruments are segmental having cut away portions 8 near the upper inner parts, which are in radial lines with the light. The flanges 7 are projected sufficiently close to the dial plates to form enclosing casings having openings at the cut away portions to permit the 50 rays of light to enter into the casings.

As shown in Figs. 1 and 2 an electric light bulb is suitably mounted at the point indicated by the number 9 and this bulb is applied to the rear face of the panel leaving the front 55 face of the panel unbroken at that point. The bulb is held in a socket as hereinafter more fully explained and in this way there is no light emitted through the front of the panel thereby enabling the light to be indirectly 60 applied to the instrument. A segmental shaped reflector 10 is placed around the electric light bulb and is preferably enamelled white on the inside, the reflector thereby seeming to contain the electric light while permitting the rays to be reflected downwardly. 65 As shown in Figs. 1 and 4 the flanges 7 co-operate with the casing for the instruments 6 to completely enclose the instruments and prevent any rays of light entering at those 70 points, the cut away portions 8 representing the points of entry for the rays of light. The side walls of the reflector 10 are so shaped as to reflect rays of light directly downwardly 75 through the cut away portions 8 of the central instrument marked 4 and rays of light are also deflected in an angular direction to enter the cut away portions of the instruments placed at the sides of the panel and reflected rays of light will almost all enter some one 80 of those openings. The arrangement of the reflector and the cut away portions or restricted openings 8 are such that reflected rays of light are focused or concentrated in a way to enter those various openings while the 85 remaining portions of the instrument are solidly encased against introduction of any light.

Referring to Fig. 3, there are prongs or projecting lugs 11 which are purposely 90 formed to operate as a three prong socket for the electric light bulb, it being usual to form these prongs with ends that can be readily bent inwardly to hold a bulb. The instruments 6 are formed with bottom portions having 95 legs 12 which are readily secured to the 100

panel adjacent to the proper opening 8 and in such position that dial readings or figures will be exposed to view from the front of the panel. The instruments are so bolted or secured to the panel portions as indicated in Figs. 1 and 3.

Having described the invention, I claim as follows:

1. In a panel assembly, an electric light placed rearwardly of the panel and concealed from the operator at the front thereof, dials for instruments placed on said panel and substantially parallel thereto and having their faces exposed at the front thereof, flanges surrounding said dial faces at the rear of the panel having cut away portions for light openings, a reflector for said electric light formed to converge the rays of light in radial lines towards the cut away portions whereby the rays of light will be projected through the light openings upon the faces of the dials.
2. In a device of the character described, the combination of a panel with a support for an electric light in said panel, a sector shaped reflector for said light, the light support and reflector being placed at the rear of the panel leaving an unbroken front wall at that point, instrument dials rearwardly of openings in the front wall of said panel, flanges projecting from said panel having cut away portions forming restricted openings, said restricted openings being placed on radial lines with the electric light and said reflector being shaped and formed to project the rays of light along radial lines along the rear face of said panel

into the restricted openings whereby the dials will be lighted up.

3. In a panel assembly, an electric light on said panel in a position to be concealed from the operator, a plurality of dials placed in openings on said panel, there being a central opening and openings at the side of the central one, flanges around said openings having cut away portions for light openings, a reflector adjacent said electric light, the central opening corresponding with the shape of the reflector to permit rays of light reflected from said light to enter said openings and the other cut away portions being of different shape but permitting reflected rays of light to enter said cut away portions.

4. In a unitary panel mounting adapted to be secured to the dash of an automobile, a panel member proper provided with a plurality of dial openings each surrounded by a flange having a cut-away portion, dials mounted in said openings respectively and positioned in substantial parallelism with said panel member, said flange extending substantially flush with said dials throughout the periphery thereof, a lamp supported in the rear of said panel and a reflector co-operating with said lamp and cut-away portions of said flanges to illuminate the faces of said dials and said flanges being disposed to reflect the light over said dial surfaces.

In testimony whereof, I have hereunto set my hand this 10th day of February, 1926.

JOHN R. PADESKY.
